R. 1.

UNITED STATES PATENT OFFICE.

GEORGE J. LOWRES, OF NEWARK, NEW JERSEY.

LENS-MOUNTING.

1,115,701.

Patented Nov. 3, 1914.

Application filed August 13, 1913. Serial No. 784,472.

To all whom it may concern:

Be it known that I, GEORGE J. LOWRES, a citizen of the United States, residing at Newark, in the county of Essex and State of New Jersey, have invented certain new and useful Improvements in Lens-Mountings; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention has reference, generally, to improvements in lens-mountings; and, the present invention is in the nature of an improvement in that class of lens-mountings set forth in my former application for Letters-Patent, filed July 19, 1913, Serial Number 780,011, with a view of providing an eye-glass or lens-mounting of the general character hereinafter set forth, the mounting being adapted to be readily secured to and removed from the lens without the usual fastening screw, the stud of the mounting being made in the form of a snap-catch which is pivotally and removably connected to a pivot-plate and is adapted to be sprung in the manner of a snap-catch over a lens-holding post which is connected with and forms an integral part of the said pivot-plate.

The present invention has for its principal object to provide a simply-constructed lens-mounting of the general character and construction hereinafter more fully set forth, in which the parts have been reduced to a minimum, the device being easily applied to lenses of varying thickness, without changing or disturbing the parts of the mounting when attaching it to the lens.

Other objects of the invention not at this time more particularly enumerated will be clearly understood from the following detailed description of the present invention.

The invention consists in the novel lens-mounting hereinafter more fully described, as well as in the details of the construction of the same.

The invention is fully illustrated in the accompanying drawings, in which:—

Figure 1 is an enlarged fragmentary elevation of an eye-glass mounting and lens, illustrating a detachable mounting embodying the principles of the present invention;

Fig. 2 is a central sectional representation of the parts illustrated in said Fig. 1, showing the lens firmly mounted and supported by the stud; and Fig. 3 is a similar sectional representation, but illustrating the manner of attaching the stud upon the edge of the lens, or removing it therefrom. Fig. 4 is a side view of the detachable stud; and Fig. 5 is a view of the same, looking in the direction of the arrow α in said Fig. 4. Fig. 6 is a side elevation of one form of combined pivot-plate and screw-threaded lens-post integrally connected therewith; and Fig. 7 is a plan view of the parts represented in said Fig. 6. Fig. 8 is a plan view of a blank for producing a slightly modified combined pivot-plate and lens-post; and Fig. 9 is a plan view of the combined pivot-plate and lens-post made from said blank.

Similar characters of reference are employed in all of said above-described views, to indicate corresponding parts.

Referring now to the figures of the drawings, the reference-character 1 indicates the usual lens provided near its marginal edge-portion and upon the major axis of the lens with a post-receiving hole 2. Arranged in this hole is a post 3 which is formed with a screw-threaded portion 4 projecting beyond the surface 5 of the lens and upon which is screwed a screw-threaded nut-like member 6. Connected with the portion 7 of said post 3, and integrally united therewith, is a suitably shaped flattened out member 8, forming a pivot-plate extending substantially in a plane at a right angle to the axis of said post 3. This pivot-plate 8 is slightly angularly bent, as at 9, see Figs. 2 and 3 of the drawings, so as to extend slightly away from the surface 10 of the lens, said angular portion being also provided near its free end-portion 11 with a suitably formed hook-receiving perforation or hole, as 12, for the purposes to be presently more fully described. When the post 3 is inserted in the hole or perforation 2 in the lens, the pivot-plate and said post are rigidly fixed in position by screwing the nut-like member 6 down upon the screw-threaded portion 4 of the post 3 and upon the surface 5 of the lens, as shown in said Figs. 2 and 3.

The combined pivot-plate and post are preferably made from a single piece of wire of the proper gage, the part 8 being bent at the proper angle to the part forming the post 3, and being suitably flattened out in a

die, or by means of a suitable tool, so as to provide the pivot-plate hereinabove mentioned.

The reference-character 13, in Figs. 1 to 7 inclusive, indicates a stud with which are integrally connected the arc-shaped strap-members or elements 14 which are adapted to be fitted upon and engage the adjacent edge of the lens. The stud is also further provided with the flanges 15 between which are arranged in the usual manner, the end-portions of the nose-bridge 16 and the nose-guards 17, the said end-portions being suitably secured in position by means of a screw 18, or any other suitable fastening means. Extending from the lower edge-portion of the inner flat surface 19 of the stud 13, is a suitably formed hook or lug, as 20, adapted to be inserted in the perforation or hole 12, hereinabove mentioned, and in alinement with said hook or lug 20 and extending from the upper edge-portion of said flat surface 19 is a forwardly extending holding plate-like member or element, as 21, adapted to be arranged upon the flat surface 5 of the lens, and having its front end-portion preferably made much thinner than the remaining portion of said plate-like member or element 21, said thin end-portion being 30 pronged or bifurcated, as at 22, all being adapted to be arranged above the element 4 of the post 3 and embracing that portion of the post 3 above said element 6, in the manner clearly represented in said Fig. 2 of the drawings. Suitably secured upon the upper surface of said plate-like member or element 21, by means of a pin, rivet, or screw, as 23, or by means of any other suitable fastening means, is a holding catch 24, made in the 40 form of a resilient spring-plate or finger, the free end-portion of which, when the hook or lug 20 has been inserted in the hole 12 and is pivotally moved in the direction of the arrow *y*, see Fig. 3, passes over the 45 free end-portion of the post 3, whereby a hole or perforation 25 in said resilient spring-plate or catch 24 is brought directly over the end of the said post, so that the said post enters the hole or perforation 25; and, 50 with the said spring-plate or catch 24 snapping into holding engagement with the post 3, it will be clearly evident that the stud 13 and lens 1 will be securely connected with 55 relation to each other, but may be just as readily separated when the spring-plate or catch 24 is raised into the dotted position indicated in said Fig. 2, and whereby the stud can be swung into the position shown in Fig. 3 of the drawings, and readily separated from its holding engagement with the flat plate 8, so that the lens and stud will be brought into their separated relation, as will be clearly understood from an inspection of 60 said Fig. 3. To prevent the hook or lug 20 from entering too far into the hole or per-

foration 12, and thereby perhaps interfering with the pivotal movements of the parts, the hook-element or lug 20 is preferably made with a pair of off-sets or shoulders as 26, which coöperate with the part 11 of the 70 flat plate 9, as will be clearly evident.

The operation of the device or mechanism in bringing the stud and lens into their snapped engaged relation, and the manner of separating the stud and lens will be fully understood from the foregoing description, and from an inspection of the several figures of the drawings, and need not, for that reason, be further described.

Instead of making the combined pivot-plate and post 3 from wire, in the manner hereinabove stated, it may be made from a flat piece of sheet-metal of the general configuration represented in Fig. 8 of the drawings, the same comprising the pivot-plate part 27 with which is connected, by means of a narrow neck-portion 28, an extension, as 29. This extension is bent, at said neck-portion 28, at an angle to the plane of the part 27, and the extension is curled in a manner so as to form a tubular post, as 30, see Fig. 9, which is also provided with a screw-threaded portion for the previously mentioned nut-like element. The construction and operation of the remaining parts of the eye-glass mounting, as will be seen from an inspection of said Fig. 8, is the same as that described in connection with the construction of eye-glass mountings illustrated in Figs. 1 to 7 inclusive, and need therefore not be further described at this time.

I am fully aware that some changes may be made in the general arrangements and combinations of the various devices and parts, as well as in the details of the construction of the said parts, comprising my novel eye-glass mounting, without departing from the scope of the invention as described in the foregoing specification, and as set forth in the appended claims. Hence, I do not limit my invention to the exact arrangements and combinations of the several devices and parts, as described in the said specification, nor do I confine myself to the exact details of the construction of the said parts as illustrated in the accompanying drawings.

I claim:—

1. In eye-glasses, in combination with a lens, a combined pivot-plate and post made from a single piece, said plate being located upon one side of the lens, and the post extending through the lens, and means upon said post for rigidly securing the combined pivot-plate and post to said lens.

2. In eye-glasses, in combination with a lens, a combined pivot-plate and post made from a single piece, said plate being located upon one side of the lens, and said post having a screw-threaded portion extending

through said lens, a nut-like element upon said screw-threaded portion of the lens for rigidly securing the combined pivot-plate and post to said lens.

- 5 3. In eye-glasses, in combination with a lens, a combined pivot-plate and post made from a single piece, said plate being located upon one side of the lens, and the post extending through the lens, means upon said 10 post for rigidly securing the combined pivot-plate and post to said lens, and the pivot-plate having a slot for pivotally and detachably connecting a stud to said pivot-plate.
- 15 4. In eye-glasses, in combination with a lens, a combined pivot-plate and post made

from a single piece, said plate being located upon one side of the lens, and said post having a screw-threaded portion extending through said lens, a nut-like element upon 20 said screw-threaded portion of the post for rigidly securing the combined pivot-plate and post to said lens, and the pivot-plate having a slot pivotally and detachably connecting a stud to said pivot-plate. 25

In testimony, that I claim the invention set forth above I have hereunto set my hand this 9th day of August, 1913.

GEORGE J. LOWRES.
